UNITED STATES PATENT OFFICE.

SMITH N. MCLOUD, OF MARYSVILLE, OHIO, ASSIGNOR TO THE DAVIS CHAIR COMPANY, OF SAME PLACE.

ADJUSTABLE HEAD-REST FOR CHAIRS.

SPECIFICATION forming part of Letters Patent No. 623,414, dated April 18, 1899.

Application filed August 25, 1898. Serial No. 689,490. (No model.)

To all whom it may concern:

Be it known that I, SMITH N. MCLOUD, a resident of Marysville, in the county of Union and State of Ohio, have invented certain new and useful Improvements in Adjustable Head-Rests for Chairs and the Like; and I do hereby declare the following to be a full, clear, and exact description of the invention, such as will enable others skilled in the art to which it pertains to make and use the same.

The invention relates to head- rests for chairs and the like, and has for its object to provide simple and efficient means for adjusting and locking the same.

15 The invention consists in a hinge connection between a head-rest and a back, said hinge having its pintle provided with a handle whereby the rest can be adjusted and locked.

20 In the accompanying drawings, Figure 1 is a side elevation of a chair-back and head-rest. Fig. 2 is a rear elevation of an improved hinge connection. Fig. 3 is a similar view, the several parts being detached. Fig. 4 is an elevation of a modified detail.

25 Numeral 1 denotes a chair-back standard pivoted to a seat 2. A back is denoted by 3, and 4 indicates a set-screw which passes through a slot in the standard and engages 30 the back. When the screw is loosened, the back can be raised or lowered and then fixed in position by tightening the screw.

35 5 indicates a head-rest connected to the back by a hinge. The part 7 of the hinge- knuckle is interiorly screw-threaded to receive a similarly-threaded pintle 9. The knuckle members 6 and 8 are without threads, as also is the part of the pintle which is situated in the knuckle member 8. The proximate 40 knuckle members 7 and 8 are toothed or serrated substantially as indicated at 10. The member 7 is carried by one hinge-leaf and 6 and 8 by the other. The pintle has a handle 11 and is provided with a collar 12, which 45 limits its endwise movement in one direction.

The handled pintle being held by this means can be turned with the effect to screw the middle knuckle member and the head-rest toward the collar—that is, toward the right—

50 thereby causing the engagement of the serrated knuckle members 7 and 8 and locking the head-rest with respect to the back. To

alter this adjustment, the pintle may be oppositely turned and the collar retracted, whereupon the pintle can be pushed endwise with 55 the effect to disengage the teeth and permit the head-rest to be turned to the desired situation, when by turning the pintle back again the locking can be renewed.

To limit the withdrawal of the pintle and 60 its collar to or near to the exact distance requisite for the operation described, it may be provided with a stop 13, as shown in Fig. 4.

The friction of the pintle in the screw-threaded knuckle member is sufficient to permit turning the head-rest by means of the handle after the serrations are disengaged. The disengaged knuckles can at any time be made to engage by a straight pull on the pintle. To lock the serrated knuckles, the pintle is 70 suitably screwed through the middle one, while collar 12 engages the hinge to prevent endwise movement of the knuckle. A reversed screwing of the pintle will disengage the knuckles. The knuckles having been 75 made to engage by a pull on the pintle, as stated, the latter can be manipulated to hold them engaged until the lock is effected or the head-rest can be directly held.

Having thus described my invention, what 80 I claim as new, and desire to secure by Letters Patent, is—

In a chair or the like, a back, a head-rest, and a hinge adjustably connecting the same, said hinge having a screw-threaded pintle, a 85 screw-threaded knuckle fixed to the rest, a knuckle fixed to the back and loosely embracing the pintle, said knuckles provided on their adjacent ends with teeth adapted for engagement, and a stop, all substantially as 90 set forth, whereby the head-rest may be moved lengthwise the pintle by its screw to disengage the knuckles and the pintle then used to adjust the head-rest in a transverse plane and to cause a reengagement of the knuckles 95 and a subsequent locking thereof.

In testimony whereof I have signed this specification in the presence of two subscribing witnesses.

SMITH N. MCLOUD.
